UNITED STATES PATENT OFFICE.

JOSEPH P. LEGGETT, OF CARTHAGE, MISSOURI.

LID FOR TEA-KETTLES, &c.

SPECIFICATION forming part of Letters Patent No. 535,252, dated March 5, 1895.

Application filed September 18, 1894. Serial No. 523,422. (No model.)

To all whom it may concern:

Be it known that I, JOSEPH P. LEGGETT, of Carthage, in the county of Jasper, in the State of Missouri, have invented a certain new and 5 useful Improvement in Lids for Tea-Kettles and Like Vessels, of which the following is a full, clear, and exact description, reference being had to the accompanying drawings, forming part of this specification.

10 My invention relates to an improved construction of lids for tea-kettles, coffee-pots, and like vessels, and my invention consists in features of novelty hereinafter fully described and pointed out in the claims.

15 Figure I is a sectional view of my improved lid, the section being taken on line I—I, Fig. II. Fig. II is a top or plan view. Fig. III is a section showing a slight modification; and Fig. IV is a like view showing still another 20 modification.

Referring to the drawings, 1 represents part of a tea-kettle, coffee-pot or other like vessel, and 2 represents my improved lid.

The object of my invention is to make a lid 25 through which liquid can be readily poured without removing the lid from the vessel, and which will be self-closing, and which will not open under the steam pressure generated in the vessel.

30 The lid consists of a downwardly tapering or cone shaped disk 3, having an open end or mouth 4, a bottom flange 3^a surrounding the open end or mouth, a vertical upper flange 5 and a horizontal marginal flange 6 that fits 35 over the upper edge of the vessel, the vertical part 5 descending into the mouth of the vessel and the tapering disk 3 providing the contracted opening 4. The opening 4 is closed by a downwardly opening valve 7. This valve 40 is in the form of a disk and is supported at its center so as to open in any direction, as indicated by dotted lines in Fig. I. I have in Figs. I and II shown it centrally supported by a spring arm 8, which connects it with the 45 part 3 of the lid, while in Fig. III I have shown it supported by a coiled spring 9, and in Fig. IV I have shown it supported on a rod 10 pivoted at 11 to the part 3 of the lid, and having an extended end provided with a balance 50 weight 12.

When liquid is poured into the lid or to any part of the surface of the valve 7 the lat-

ter opens and being centrally supported it will tilt and open in either direction, according to the direction in which the stream may fall 55 upon it, thus avoiding, to a great extent, the splashing or rebound of the liquid. When the liquid has passed from the lid into the vessel, the valve will be automatically closed and when steam pressure is generated within 60 the vessel it tends to hold the valve more firmly to its seat rather than to open it.

To further provide against the splashing of the liquid from the lid as it is poured in I employ a perforated or gauze diaphragm 13 extending across the lid at the base of the vertical portion 5 of the lid. This diaphragm is held in place by a ring 14 tightly pressed in place and clamping the up-turned edge 13^a of the diaphragm between it and the vertical 70 part 5 of the lid. The ring 14 has a horizontal flange 15 fitting over the horizontal flange 6 of the lid and the flange 15 terminates in a marginal bead 16 which forms a finish to the exposed edge of the lid. 75

While the liquid passes freely through the diaphragm 13, yet this diaphragm will act to a great extent to prevent any rebound or splashing of the liquid from the lid when it strikes the inclined sides 3 of the lid and the 80 valve 4.

The lid may be provided with suitable means for lifting it from the vessel, as for instance with a bail 17 as shown in Figs. I and II, or with knobs 18, as shown in Figs. III and IV. 85

The valve 7 may, if desired, be formed somewhat crowning as shown by the dotted line 19, Fig. IV, instead of being made flat as indicated by the full lines.

I have shown the spring 9 in Fig. III connected at its upper end to the diaphragm 13, the valve thus being supported centrally from the diaphragm by means of the spring. 90

I claim as my invention—

1. As a new article of manufacture a lid for vessels comprising a body portion, a downwardly opening valve, closing the mouth of the body portion, means for supporting the valve, and a wire gauze diaphragm located in the body portion over the valve; substantially 95 as described.

2. As a new article of manufacture a lid for vessels comprising a body portion, a downwardly opening disk-valve, closing the mouth 100

of the body portion, means for supporting the valve loosely from its center so as to enable it to tilt, in any direction, on its central support, from one side of the opening to the other 5 side thereof, a wire gauze diaphragm located in the body portion above the disk-valve, and a ring for holding the diaphragm in place; substantially as described.

3. In a lid for vessels, the combination of a 10 body portion having a cone shaped part 3, a vertical part 5, and a horizontal marginal flange 6, a perforated diaphragm located at

the base of the vertical part 5 of the lid, a ring for holding said diaphragm in place, and which is composed of a vertical part, a horizontal part, and a marginal bead, a valve 4 closing an opening at the base of the cone shaped part 3 of the lid, and a spring centrally supporting the valve, substantially as set forth. 15

JOSEPH P. LEGGETT.
